UNITED STATES PATENT OFFICE.

WILLIAM MAYO VENABLE, OF PITTSBURGH, PENNSYLVANIA, ASSIGNOR TO BLAW-KNOX COMPANY, A CORPORATION OF NEW JERSEY.

ART OF MAKING CEMENTITIOUS MIXTURES.

Application filed March 31, 1925. Serial No. 19,694.

This invention relates to improvements in the art of making cementitious mixtures such as concrete and the like and is particularly directed to the apportioning of sand 5 and water for a batch of concrete.

It is well known in the art that when perfectly dry sand of uniform quality is measured by bulk, a given bulk container, filled always to the same level, in the same manner, 10 will always contain the same weight of sand; also that if the container be entirely filled with water, and sand be poured into it slowly in a uniform manner until the container is level full of sand and water, the excess water 15 overflowing, the total weight of sand and water in the container will always be the same, no matter whether the sand be wet or dry before being poured into the container.

However, moist sand, measured in a container without an excess of water, will not always pack to the same extent, and the total weight of sand so measured will be found to vary from batch to batch. As it is impracticable to obtain perfectly dry sand in the 25 large quantities used in concrete construction, and as sand must have water as well as cement and other materials mixed with it in order to make concrete, bulk measurement of the sand may be rendered more accurate by 30 measuring the sand under water, or in a completely saturated condition.

It happens that generally it is necessary, in mixing concrete, to have a larger quantity of water in the mix than necessary to saturate the sand completely. As a consequence, 35 it is practicable to measure the sand in a saturated condition, and to dump the saturated sand with the water contained in it into the mixer, adding such amount of water as may 40 be necessary to give the desired consistency, which amount depends upon the amount of cement used, and other factors, but is uniform as long as those factors are kept uniform. Therefore, by measuring the sand in 45 a saturated condition, the variation in amount of water to be added, which is serious when moist sand, not uniform in water content is employed, is eliminated, and an important cause for lack of uniformity in 50 strength of concrete—variation in the amount of water from batch to batch—is eliminated.

These facts have hitherto been used in 55 making mixtures, but the methods employed have had disadvantages which are not en-

countered in the method to which this invention relates. One method is to place in the container more than enough water to completely saturate a batch of sand, and to sift sand therein until the container is filled to 60 an overflow level, at which the surplus water escapes, leaving saturated sand up to that overflow level. This method has practical difficulties. In the first place, it is slow because the sand must not be shaken into the 65 water more rapidly than the grains can be thoroughly wetted, as otherwise air is entrapped with the sinking sand. In the second place, it is difficult to gauge the amount of water and it is necessary always to waste 70 more water by overflow than is desirable, and with this waste water some of the sand always is carried off.

Furthermore an excess of sand usually accumulates on top of the saturated sand above 75 the overflow level of the water which makes the process additionally inaccurate.

From the foregoing it will be readily seen, that, in order to render such a process accurate, considerable care is required on the 80 part of the operator and the time necessary to so prepare the sand with water is many times greater than that required to measure the sand and water separately, without inundation, in the usual way formerly employed. In addition, it is pointed out that when sand is poured into standing water there is a great deal of splash and slop and a considerable amount of sand is washed over with the excess of water. 85

Thru my invention I aim to overcome the above defects in a simple, expeditious and economical manner particularly as regards 90 time.

I introduce sufficient water to saturate the 95 sand and to fill the voids therein without putting the sand in suspension thus avoiding the necessity of waiting for the sand to settle and consequently shortening the time interval between successive withdrawals for 100 the batch. Stated more specifically I propose to saturate by percolation, so to speak, an amount of sand in excess of the amount to be withdrawn for a batch and subsequently to withdraw a predetermined amount of the 105 so saturated sand. Hence a mixture of sand and water is made and held in reserve by adding water to the relatively dry sand in such amounts as will always produce complete saturation and this without waste and 110

without pre-measurement of the water. It is also to be pointed out that by adding the water to the sand, without putting the sand in suspension, the time taken by previous methods to permit the sand to settle thru the water and to complete its settlement before delivery is entirely eliminated—a very considerable saving of time.

When sand and water are prepared by my method, it is a fact proven by experience that the sand and water will flow together from the receptacle into the measuring vessel without change of the mixture so that the actual quantity of sand and the actual quantity of water in the measuring vessel at the time it is filled to the overflow level are constant; that is to say, the method gives a uniform measure of both sand and water, substantially invariable for a given size receptacle.

Another point of importance is the fact that where saturated sand is allowed to flow into a measuring receptacle there is no splash or slop and hence no waste.

Another object is the application of the liquid for saturating the sand in such a manner that a head of substantially dry sand may be maintained above the saturated portion, such dry sand gravitating to the region of saturation as sand is withdrawn for the batch.

A further object of the invention is the provision of means for adding sufficient water to saturate the relatively dry sand which replaces that removed for the batch.

Still another object is the provision of a novel valve peculiarly adaptable for use in connection with an apparatus as herein set forth.

Another object is the provision of a supplementary water measuring device for adding a predetermined quantity of water to the measured saturated sand after measurement thereof.

Further advantages of a mechanical nature will be apparent when comparing the apparatus for carrying out the method herein disclosed, with other systems and apparatus now in use.

The foregoing together with such other objects as may hereinafter appear, or are incident to my invention, I obtain by means of a construction which I have illustrated in preferred form in the accompanying drawings, wherein:

Fig. 1 is a partial longitudinal elevation of and section thru an apparatus utilized in carrying out my invention and

Fig. 2 is a detail plan view of the delivery valve removed from the apparatus, and showing the valve in open position in full lines and in closed position in dotted lines.

Referring now to Fig. 1 it will be seen that the apparatus in general, comprises a bin A divided into compartments B and C, the com-

partment B, in this instance being used for crushed stone and the compartment C for sand; a measuring device D for apportioning material from the compartment B; a measuring receptacle E for receiving material from the compartment C; and a receiving device F which may very well be a concrete mixer.

The compartment C, hereinafter referred to as "a delivery receptacle" is divided into an upper portion 7 having an inlet for the sand to be prepared for delivery and an open bottom; and a lower portion 8 having an outlet 9 provided with a control valve 10. This lower portion 8 may be of a conical or inverted pyramidal shape and of such dimension at the top as to receive the lower part of the upper portion 7 of corresponding shape which extends part way into and is spaced as at 11 from the lower portion 8. In the particular device shown the space 11 extends around only three sides but it is to be understood that in other instances it may be desirable to have the space extend all way around as would particularly be the case if the compartment B were omitted. The lower portion 8 of the delivery receptacle C is water tight as is the bulk head or partition 12 which divides the bin A.

Having thus described the construction of the delivery receptacle C it will be seen that when it is filled with sand, the sand takes a natural slope between 7 and 8 as indicated at 13 exposing surface sand to the space 11 above mentioned. As it is a purpose of this invention to have a reserve of saturated sand always in readiness, from which, certain amounts may be withdrawn for the batch, that is as long as there is dry or substantially dry sand in the receptacle C, I will now describe the manner in which this is accomplished.

A water level 14 is maintained above the exposed surface sand indicated at 13, by means of a float valve 15 in a suitable tank 16 which communicates with the receptacle C thru the pipe connection 17 so that the level of water in the receptacle and tank are kept the same. The float valve 15 controls the admission of water thru the water supply pipe 18 which in this instance is shown leading into the lower portion of the delivery receptacle C somewhat above the water level 14, and hence regulates the water level therein. Thus, a considerable amount of standing water is maintained between the surface sand 13 and the water level 14 for keeping the sand filled with water and this without putting the sand in suspension as will further appear. In this connection it is to be understood that the pipe 17 might be made large enough to carry the water supply to the receptacle C in which case the pipe 18 would discharge into the tank 16; or that the pipe 18 might discharge at any other con-

venient place, even into the receptacle C at some higher elevation if desired. Furthermore it is to be observed that the space 11 may be made large enough so that the float 5 valve could be placed directly in the space, thus eliminating the auxiliary tank 16 entirely. Certain advantages as for instance accessibility of the parts have led to the particular arrangement shown in the drawings.

10 The operation of the device as thus far described is as follows:

Let us consider for the purpose of illustration a device of the proper size to furnish sand to be measured out for use with a one-15 yard concrete mixer. In that case the discharge of the valve 10 will be made approximately 4½ inches in diameter and the water supply pipe 18 approximately 2 inches in diameter and it will be desired to draw off the 20 necessary amount of sand once every minute or perhaps every one-half minute at times, depending upon whether the sand is to be discharged directly into the mixer, or into containers for hauling to some other point, for 25 it is quite feasible to make this device serve more than one concrete mixer if desired. We will then assume that the delivery receptacle C is full of sand, the water level in the lower portion 8 thereof at the elevation 14, and the 30 sand saturated with water and the voids filled with water to this elevation entirely across the receptacle C. The valve 10 is then opened and a 4½ inch stream of sand and water flows out and into the measuring receptacle E.

25 The immediate result of the flowing out of the saturated sand is that the dry sand from the upper portion 7 of the receptacle C settles into the lower portion 8 and the water level in the tank 16 lowers from the level 14 to 40 some lower level. Of course when this occurs there is a lowering of the water level in the space 11 between 7 and 8 and the float valve 15 is opened, discharging water thru pipe 18 into the lower portion 8 of the receptacle. 45 It would then be possible to draw off sand and water from 8 until practically dry sand reaches that level. In practice I propose to make the capacity of the portion 8 of the receptacle of such size that it will never be 50 likely that the quantity of sand drawn off at one time will allow dry sand to reach the valve 10. When, however, the valve 10 is closed, water will continue to percolate or seep into the sand at 13, without putting the 55 sand in suspension and will gradually restore the water level to the level 14.

I have found from actual experience that with a properly dimensioned device as above exemplified, the amount of excess water 60 drawn off with the sand is negligible so that the sand drawn off at the valve 10 carries substantially but little more water than necessary to saturate it and to fill all the voids, hence my device is not wasteful of water and 65 is very accurate in the measurement thereof.

Reverting now to the construction of the measuring receptacle E it will be seen that it is pivotally mounted below the valve 10, and that any suitable means may be provided for holding the receptacle E in mixture receiving 70 position. When measuring out the mixture of sand and water the valve 10 is opened and the mixture is allowed to run into the measuring receptacle E until it is entirely filled, the proportion of sand to water in the measuring receptacle E being the same as that in the premixing receptacle 8 as before pointed out. The contents may be then discharged into the mixer or other receiving device F, by tipping the measuring receptacle E. 75

In this connection it is pointed out that should the operator fail to close the valve 10 at the proper time, the mixture would overflow at 19, the surplus sand being carried along by the water so that the mixture contained in E would not, even under these circumstances, be excessive. Hence I am always enabled to get the same volume of the mixture in a batch without having to resort to other means of control. 80

In order to utilize the same measuring receptacle for various sized batches of cementitious mixtures I have shown the bottom 21 thereof adjustable to alter its volumetric capacity. When the capacity is set to meet the 95 particular requirements of the specifications the measured amount is substantially invariable and will not change until the adjustment of the capacity is changed.

Another feature of my invention is the 100 auxiliary water measuring device indicated as a whole by the reference letter G.

It is sometimes desirable to supply a little more water to the mix than that which is contained in the mixture in the receptacle E, 105 therefore I have provided an auxiliary water measuring device by means of which a predetermined amount of water may be added to each batch. The device G, comprises a tank 22, having a valve controlled water inlet 110 23, and a valve controlled water outlet 24, in this instance leading to the mixer; and a weighted bucket 25, having adjustable means 26 whereby it may be raised and lowered in the tank 22 to alter the capacity of the tank. 115 A pointer 27 and scale 28 are provided to indicate the amount of water the tank will hold when filled to the overflow 29.

In operation the valve in the inlet line 23 is opened to admit water into the tank 22 until it overflows at 29 at which time the valve is closed. The tank now contains a predetermined amount of water which upon opening of the valve in the outlet line 24 may be discharged into the mixer or whatever other 125 form of device F is being employed. This of course may be done either while the container is being filled or after it has been filled as desired. By supplying additional water in this manner I am enabled to cleanse the interior 130

parts of the mixer in a very convenient manner.

Turning back now to the particular construction of the valve 10, the general function of which has been hereinbefore described, it will be seen that the valve comprises a body or casing 30 preferably made in two parts, an upper and lower, the whole being secured to the receptacle C; and a rotatable valve plate 10 or disc 31 provided with a discharge passage or opening 32.

The lower part of the body 30 is provided with a seat 33 in the form of an upwardly projecting nipple, on which the valve disc 31 rests, additional support being provided by the screws 34. As best seen in Fig. 2, the discharge opening 32 in the disc 31 is elongated while the opening and nipple 33 of the valve body are circular, so that when the valve is in open position as shown the disc covers the edge 34 of the nipple on one side and leaves the balance uncovered. It will be noted that by this arrangement no sticks, stones, grass or other obstructions can get between the outside of the nipple and the opening in the disc on the covered side. As the other side is not covered it is possible for obstructions to settle on that side between the nipple and disc so that in closing the valve to the dotted line position 35 there will be no interference.

It is also to be noted that the disc will soon become entirely surrounded by sand both above and below, except at the nipple. It is for this reason made circular so that it may 35 turn under these circumstances without having to displace any sand and thus not only work easily, but not be subject to packing. The opening at the pipe, however, will always relieve the pressure, and there is no necessity 40 of providing any means for holding the disc down against the pipe.

While I have shown the sand saturating and measuring device in connection with a stone bin and batcher in a manner to form a 45 unit it is to be understood I might employ the stone device as a separate unit leaving the sand device also a separate unit as may best suit particular conditions.

It is obvious that under ordinary operating conditions there will be very little surplus water in the measuring receptacle E, but in the event that any excess water should find its way thereto, which would be at the tail end 50 of delivery, it would wash over the spout 19.

55 I claim:—

1. In the herein described process of preparing and measuring sand and water for cementitious mixtures, the steps which consist in delivering sand into a suitable delivery receptacle and in percolating water, to the saturation point, into the voids of the sand particles, in the lower portion of such receptacle.

2. In a system for preparing cementitious mixtures employing a suitable sand delivery

receptacle to which sand is supplied and from which sand is to be periodically withdrawn, the steps which consist in preparing sand for withdrawal by percolating water into, and filling, the voids in the sand in the receptacle 70 as it is withdrawn therefrom, without putting said sand in suspension, and in controlling such percolation by the withdrawal of sand.

3. In a system for preparing cementitious mixtures employing a suitable sand delivery receptacle to which sand is supplied and from which sand is to be periodically withdrawn, the step which consists in preparing sand for withdrawal by percolating water into the voids in the sand in the receptacle, such water 75 being introduced below the normal level of the sand in the receptacle.

4. In a system for preparing cementitious mixtures employing a suitable sand delivery receptacle to which sand is supplied and from which sand is to be periodically delivered into a measuring receptacle, the step which consists in saturating more sand with water in the delivery receptacle than the measuring receptacle will hold.

5. The method of preparing and measuring sand and water into batches for concrete mixing, which consists in saturating a predetermined quantity of sand, in maintaining a head of dry sand on said saturated sand, in 90 withdrawing a predetermined quantity of saturated sand, and in adding sufficient water to saturate the dry sand which replaces the withdrawn sand.

6. In the process of handling, storing and delivering sand and water for use in cementitious batches, the step which consists in maintaining a predetermined part of the sand in the sand receiving and delivery receptacle saturated.

7. In the art of making cementitious mixtures those steps which consist in storing a quantity of sand in a suitable receptacle, from the lower portion of which it may be withdrawn for the batch, and in automatically maintaining liquid substantially constantly at a given level in the lower portion of the receptacle to saturate the sand in that portion.

8. In the art of making cementitious mixtures those steps which consist in storing a quantity of sand in a suitable receptacle, from the lower portion of which it may be withdrawn for the batch, in maintaining liquid in the lower portion of the receptacle to 115 saturate the sand in that portion, in withdrawing a predetermined batch of the saturated sand and in adding liquid to replace that withdrawn and to saturate the portion of sand from the upper part of the container 120 which replaces that withdrawn.

9. The method of saturating and measuring sand into batches which consists in feeding substantially dry sand from a supply bin into a hopper so that when the hopper is 130

filled the sand therein and that in the supply bin are one mass, in adding sufficient water to saturate the sand in the hopper, in measuring out a predetermined quantity of the 5 saturated sand and in simultaneously flowing sufficient water into the hopper to saturate the dry sand which replaces the removed batch of saturated sand.

10. The method of saturating and measuring sand into batches which consists in supplying a suitable container with sand, in introducing liquid to the supply of sand between the top and bottom thereof and thereby saturating the sand below the point of liquid introduction, in withdrawing a predetermined quantity of the saturated sand, and in controlling the introduction of the liquid so as to maintain a substantially constant reserve of saturated sand.

15. 11. The method of measuring sand and water into batches which consists in saturating a portion of a mass of sand, in withdrawing a predetermined quantity of sand from the saturated portion, and in adding water 25 to the mass of sand to maintain a constant reserve of saturated sand to an amount not less than the quantity to be withdrawn at any one time.

12. In the art of making cementitious mixtures those steps which consist in storing a quantity of sand in a suitable receptacle, from the lower portion of which it may be withdrawn for the batch, in maintaining liquid 35 in the lower portion of the receptacle to saturate the sand in that portion, in adding liquid to replace that withdrawn with the saturated sand, and in adding a predetermined quantity of liquid to the withdrawn saturated sand.

40. 13. In the art of making cementitious mixtures those steps which consist in storing a quantity of sand in a suitable receptacle, from the lower portion of which it may be withdrawn for the batch, in maintaining liquid 45 in the lower portion of the receptacle to saturate the sand in that portion, in withdrawing a predetermined batch of the saturated sand, in delivering said measured batch into a receiving container, and in adding a predetermined quantity of liquid thereto.

14. In apparatus for preparing sand and water for cementitious mixtures the combination of a delivery receptacle having an inlet opening for substantially dry sand and an 55 outlet opening for saturated sand, and means for percolating water from below the normal sand level into the voids of the sand particles to the point of saturation.

15. In apparatus for preparing sand and 60 water for cementitious mixtures the combination of a delivery receptacle having an inlet opening for substantially dry sand and an outlet opening for saturated sand, and means for percolating water into the voids of 65 the sand particles, the point of admission of

the water being in the lower portion of such receptacle.

16. In apparatus for making cementitious mixtures the inclusion of means for creating a saturated mixture of sand and water without putting the sand in suspension. 70

17. In apparatus for making cementitious mixtures the inclusion of means for creating a saturated mixture of sand and water without putting the sand in suspension, and means 75 for periodically withdrawing batches of such mixture.

18. In apparatus for preparing sand for cementitious mixtures the combination of a delivery receptacle having an inlet opening 80 for substantially dry sand and an outlet opening for saturated sand, and means for percolating water into the voids of the sand particles, together with means for maintaining a substantially constant reserve of water 85 for percolation.

19. In apparatus for preparing sand for cementitious mixtures the combination of a delivery receptacle having inlet and outlet openings and a contracted portion between 90 them providing a dry sand compartment above the contracted portion and a saturated sand compartment below and means for saturating the sand in the lower compartment.

20. In apparatus for preparing sand for cementitious mixtures the combination of a sand delivery receptacle having its upper portion extending partway into and spaced from the lower portion and means for introducing liquid to said receptacle and for automatically maintaining a substantially constant level of the liquid in the space between the upper and lower portions thereof to saturate the sand in the lower portion of the receptacle. 95

100. 21. In apparatus for preparing sand for cementitious mixtures the combination of a sand delivery receptacle having its upper portion extending partway into and spaced from the lower portion, the sand in said receptacle in its natural slope forming a bottom for the space, means for introducing water to said space for saturating the sand by percolation, and means for maintaining standing water in said space. 110

115. 22. In combination with apparatus for handling saturating and delivering sand for use in cementitious batches, an auxiliary water measuring device comprising a reservoir having valve controlled water inlet and outlet, and means for altering the volumetric content of said reservoir, said water outlet leading the contents of the reservoir to the receiving medium for the batch of sand. 120

125. 23. In combination with apparatus for handling saturating and delivering sand for use in cementitious batches, an auxiliary water measuring device comprising a reservoir having valve controlled water inlet and outlet, and an adjustable non-buoyant mem- 130

ber extending into the reservoir for altering the contents thereof, said water outlet leading the contents of the reservoir to the delivered batch of sand.

24. In apparatus for making cementitious mixtures, the inclusion of means for creating a saturated mixture of sand and water without putting the sand in suspension, and means for periodically withdrawing batches of such mixture, together with means for automatically maintaining said mixture in an amount at least as great as that withdrawn for a batch.

25. In the art of making cementitious mixtures, the method which consists in introducing liquid and granular material to a suitable container, and in initiating and carrying on a combining of the two from below.

26. In the art of making cementitious mixtures, the method which consists in introducing liquid and granular material to a suitable container, and in initiating and carrying on a combining of the two from below, to the saturation point of the granular material.

27. The method of preparing granular and liquid materials for making cementitious mixtures, employing a mixing receptacle, which consists in maintaining the granular material constantly above a given level in said receptacle, and in maintaining a head of liquid on the material at said given level.

28. In the art of making cementitious materials, the method which consists in introducing into, and storing for discharge from, a container, said sand and water, and in maintaining a head of sand and a head of water each above the point of its introduction to the container.

29. The method of combining granular and liquid material which consists in passing a substantially solid mass of the granular material downwardly through a containing means, from the lower part of which it is withdrawn as needed, and in introducing the liquid into said containing means below the point of introduction of the granular material.

30. The method of combining granular and liquid material which consists in passing a substantially solid mass of the granular material downwardly through a containing

means, from the lower part of which it is withdrawn as needed, and in introducing the liquid into said containing means under a constant head, regardless of withdrawals of 55 the material.

31. The method of proportioning granular and liquid ingredients of a mixture to be delivered from a receptacle by batches which consists in feeding a granular material to the 60 receptacle and in maintaining in said receptacle a substantially constant level of liquid at a height below the normal level of the granular material.

32. The method of proportioning granular and liquid ingredients of a mixture to be delivered from a receptacle by batches which consists in feeding a granular material and liquid to the receptacle, in drawing off batches of mixed material, and in maintaining in said receptacle a substantially constant level of liquid at a height sufficient to maintain a predetermined supply of completely saturated granular material.

33. In a system of proportioning liquid 75 material and aggregate employing a suitable receptacle to which aggregate is supplied and from which it is to be discharged, the step which consists in preparing the aggregate for discharge by introducing liquid into the receptacle at a level below the normal level of the aggregate in the receptacle.

34. In the art of measuring sand and water for a cementitious mixture, the method which 85 consists in combining water and sand at least to the saturation point of the latter, and in subsequently measuring them together.

35. In the art of measuring sand and water for a cementitious mixture, the method, employing a delivery receptacle and a measuring container, which consists in combining water with sand in said receptacle at least to the saturation point of the latter, in periodically filling said container from said receptacle, and in maintaining a constant supply of 90 the saturated mixture in said receptacle not less in amount than the volume of said container.

In testimony whereof, I have hereunto signed my name.

WILLIAM M. VENABLE.
